UNITED STATES PATENT OFFICE.

JOHN POGORZELSKI, OF PHILADELPHIA, PENNSYLVANIA.

COMBINED TABLE AND MANGLE.

Application filed January 26, 1922. Serial No. 531,997.

To all whom it may concern:

Be it known that I, JOHN POGORZELSKI, a citizen of Poland, residing at Philadelphia, in the county of Philadelphia and State of Pennsylvania, have invented certain new and useful Improvements in Combined Tables and Mangles, of which the following is a specification.

This invention relates to certain new and useful improvements in combined tables and mangles and has particular reference to the provision of a table structure having a sliding drawer, an ironing mangle associated with the drawer adapted for use when the drawer is slid to an open extended position.

The primary object of the invention resides in the provision of a combined table and mangle wherein the table is provided with a sliding drawer, the sliding drawer having a hinged cover portion constituting an ironing table while link devices connected to the drawer carry a shiftable rack bar adapted for engagement with a heated mandrel for pressing flat work, the drawer being provided with a compartment to contain the mandrel and rack bar that is detachable from the link devices and other articles relating to the device.

With the above general objects in view and others that will appear as the nature of the invention is better understood, the same consists of the novel form, combination and arrangement of parts hereinafter more fully described, shown in the accompanying drawing and claimed.

In the drawing, wherein like reference characters designate corresponding parts through the several views,

Figure 1 is a front elevational view of the combined table and mangle constructed in accordance with the present invention,

Figure 2 is a top plan view of the same with the sliding drawer of the table moved to an open position, with the clothes mangle set up in an operative position,

Figure 3 is a cross sectional view taken on line III—III of Figure 2 showing the presser rack bar engaging the mandrel on the cover which constitutes the ironing table, and showing the link connection between the rack bar and the drawer, and

Figure 4 is a transverse sectional view taken on line IV—IV of Figure 2 showing the link devices connecting the presser rack

bar with the hinged cover of the table drawer constituting the ironing table shown in an open position by dotted lines.

Referring more to the accompanying drawings there is illustrated a combined table and mangle, the table embodying a top section 1 mounted on corner legs 2 with braces of the usual character while a drawer 3 is slidably disposed beneath the table top.

The sliding drawer carries forward supporting legs 4 and is composed of a bottom wall 5, a rear wall 6, front wall 7, and side walls 8, a central partition 9 extends longitudinally and centrally of the drawer, while a cross partition 10 divides the drawer into separate compartments 11, 12 and 13. The compartment 13 is closed at its upper side by a fixed cover 14, a hinged cover portion 15, the side walls 8 and the partition 9 being cut away as at 16 to provide a clearance for the hinged swinging movement of the rear edge of the cover portion 15, clearly shown in Fig. 2. When the drawer is in the closed position shown in Fig. 1, the same is entirely housed beneath the table top 1 while the legs 4 as illustrated are disposed in proximity of the adjacent corner legs 2 the device only occupying the usual space of an ordinary table.

The ironing or mangle device associated with the table and drawer includes the provision of a pair of spaced blocks 17 mounted in the drawer compartment 13 beneath the fixed cover portion 14, the latter having an elongated slotted opening 18 therein overlying the space between the blocks 17. A link 19, shown more clearly in Fig. 3, is pivotally mounted at one end upon the pin 20 extending between the blocks 17, the other end of the link extending upwardly through the slotted opening 18 in the fixed cover section 14 of the front drawer compartment 13,

and having pivotally connected as at 21 to the upper end, another link 22. A presser rack bar 23 best illustrated in Figures 2 and 3, is pivotally connected at one end as at 24 to the free end of the link 22, the upper surface of the opposite end of the rack bar carrying a gripping handle 25 while a handle knob 26 is carried by the rack bar adjacent the pivot point 24 with the link 22. The rack bar 23 is comparatively wide and the lower or bottom face thereof is corrugated as at 27 for engagement with a mandrel 28.

From the above detailed description of

110

the device it is believed that the construction and operation thereof will at once be apparent, it being noted that the cover section 15 for the drawer compartment 13 constitutes the top of the ironing table, a flat fabric sheet *a* resting upon the table top section 15 with the mandrel 28 heated in any suitable manner being engaged by the rack bar 23 to be rolled over the fabric for the purpose of ironing or smoothing the same. The rack bar 23 is gripped by the handle 25 and the knob 26 and suitable pressure thereon will press the mandrel 28 into positive engagement with the cloth or fabric *a*, movement of the rack bar in opposite directions, being limited by the link connection 19—22 with the blocks 17. When the mangle is out of use, and it being desired to dispose the sliding drawer beneath the table top 1, the pivot pin 24 connecting the rack bar to the link 22 is removed and the links 19 and 22 permitted to fold upon themselves and be disposed through the slot 18 into the compartment 13 of the drawer. The rack bar 23 may also be placed in the drawer compartment 13 beneath the hinged cover section 15 while the mandrel 28 and other articles may be placed in either of the compartments 11 or 12. When so disposed, the drawer is slid to the closed position as shown in Fig. 1.

While there is herein shown and described the preferred embodiment it is believed that the construction and operation as well as the advantages of the present invention will

be readily understood and appreciated by those skilled in the art.

Minor changes may be made in the invention without departing from the spirit and scope thereof.

What is claimed is:—

1. The combination with a table including a top, supporting legs, a sliding drawer disposed beneath the table top, a transverse partition therein dividing the drawer into separate compartments, a fixed cover section for the forward compartment and a hinged cover section for the remaining portion of said compartment, the said fixed cover portion having an elongated slot therein, a pair of connected links, the end of one link pivoted within the permanently covered compartment portion with the links extending through the cover slot, the hinged cover portion constituting an ironing table, a rack bar pivoted to the free end of the link and a mandrel between the rack bar and the hinged cover section.

2. The combination of a table including a top section and supporting legs, a sliding drawer carried by the table, a hinged cover section for a portion of the drawer constituting an ironing table, a rack bar having link connection with the drawer and adapted to be positioned in overlying relation with respect to the hinge cover of the drawer section, and a mandrel interposed between the rack bar and the cover section of the drawer.

In testimony whereof I affix my signature
JOHN POGORZELSKI.
